UNITED STATES PATENT OFFICE.

CHARLES TUCKER, OF MATTAPAN, MASSACHUSETTS.

COVERED WAGON.

SPECIFICATION forming part of Letters Patent No. 279,047, dated June 5, 1883.

Application filed April 17, 1883. (No model.)

To all whom it may concern:

Be it known that I, CHARLES TUCKER, of Mattapan, in the county of Suffolk, of the Commonwealth of Massachusetts, have invented a new and useful Improvement in Covered Wagons; and I do hereby declare the same to be described in the following specification and represented in the accompanying drawings, of which—

10 Figure 1 is a transverse section, and Fig. 2 a longitudinal section, of a covered wagon-body provided with my invention, the nature of which is defined in the claims hereinafter presented. Fig. 3 is a horizontal section of 15 two of the grooved bows of the cover-frame, such section also showing a section of a curtain-runner arranged between such bows, and adapted to them by two dovetailed flexible strips. This latter section exhibits the parts 20 on an enlarged scale.

The frame for supporting the cloth or leather cover A of the wagon-body B is composed of a series of bows, C, D, E, and F, arranged at suitable distances apart, and extending upward from and over the said body in manner as represented. The said cover extends over the bows and down to the body in the usual manner, except in the spaces between 25 the vertical parts of two front bows, wherein 30 vertically-movable curtains are employed. The cover also extends down in rear of the arch of the rearmost bow, between which there is adapted to the opening, at the rear of the wagon, and between the body thereof and the 35 said arch, a curtain to play up and down between the grooved and bent sections supporting the arch of the bow.

In Fig. 1 the rear curtain is shown at H', and one of the side curtains at H. 40 Each of the front bows, C and D, is in two sections, a and b, each of which below the arch of the bow is straight. In the crown of the arch one section extends underneath and against the other. Each section throughout 45 its length has within it a dovetailed groove open along one side of the section, the dovetailed groove being shown at c in Fig. 3, and its opening at d. This groove is a channel formed lengthwise in the bow and open along

one side of it. The openings d of the bow C 50 face those of the next one, D, and within each section of the bow is a flexible dovetail, G, a transverse section of which is shown in Fig. 3. The curtain H of each side of the cover is fixed at its opposite edges to the long 55 dovetails of the two bows. On moving upward the said curtain the dovetails will slide in the bows and into the arch of each. When the curtains are raised up, the portion of one in the crown of the arch will overlap the corresponding part of the other.

The rearmost bow, F, of the wagon-body is composed of an arched piece, f, and two dovetailed grooved sections, g g', from which the arch springs at its feet. Each of the said 65 sections is bent and extended horizontally into the cover, in manner as shown at g' in Fig. 2. The grooves of the section open toward each other, and should have flexible dove- 70 tails adapted to them, and the curtains fixed to such dovetails, as hereinbefore described, from which it will be seen that the curtain can be forced upward between the upper horizontal parts of the sections, or be drawn down 75 between their vertical portions, such being to either open or close the end of the wagon-body cover.

The wagon-top so made can be wholly closed on either side; or the curtain to such side may be raised, so as to open the top at such side; 80 and the top may be opened in rear by raising the end curtain.

In order to complete the arch of each of the bows C and D, I apply thereto a curved supplementary section of pieces, m, bent and arranged as represented in Fig. 1.

I claim—

1. The wagon-body-cover-supporting frame, substantially as described, composed of the dovetail grooved bows C D, one or more 90 plain bows, E, the arched pieces f, and the two dovetail grooved and bent sections g g', constructed and arranged substantially as set forth.

2. The combination of the supplementary 95 section m with the two dovetailed grooved sections of each bow C and D, arranged to lap together at their upper parts, as represented.

3. The combination of side and end curtains provided with flexile dovetails, as described, with the wagon - body - supporting frame, composed of the bows C D, one or more plain bows, E, the arched piece f, and the two dovetail grooved and bent sections g g', arranged substantially as set forth, the said cur-

tains being adapted to the said frame, and it being provided with a cover of cloth or other suitable material, essentially as explained.

CHARLES TUCKER.
